UNITED STATES PATENT OFFICE.

WULF SILVERMAN, OF NEW YORK, N. Y.

CONTAINER FOR CIGARS AND CIGARETTES.

Application filed January 27, 1923. Serial No. 615,282.

To all whom it may concern:

Be it known that I, WULF SILVERMAN, a citizen of the United States, and a resident of New York city, county and State of New York, have invented certain new and useful Improvements in Containers for Cigars and Cigarettes, of which the following is a specification.

This invention relates to containers for 10 cigars and cigarettes.

The invention has for one of its objects to provide a container that will be pleasing in appearance and from which the articles contained can be readily dispensed or with- 15 drawn.

Another object of the invention is to provide a device of the character described so constructed and arranged that cigars and cigarettes can be entirely enclosed therein 20 when desired but having a cover member so constructed as to render the articles readily accessible when the container is open.

Further objects of the invention will appear from the following description taken in 25 connection with the drawings which form a part of this application and in which,

Fig. 1 is a perspective view showing the container closed.

Fig. 2 is a sectional elevation showing the 30 parts arranged as illustrated in Fig. 1.

Fig. 3 is a view similar to Fig. 2 but showing the cover in elevated position and the container adjusted to a position in which the cigars and cigarettes are accessible.

Fig. 4 is a sectional elevation taken sub- 35 substantially on line 4—4 of Fig. 3.

Fig. 5 is a sectional elevation taken sub- 40 substantially on line 5—5 of Fig. 2.

Fig. 6 is a sectional elevation taken sub- 45 substantially on line 6—6 of Fig. 3.

Fig. 7 is a sectional elevation taken sub- 50 substantially on line 7—7 of Fig. 3, and

Fig. 8 is a sectional elevation taken sub- 55 substantially on line 8—8 of Fig. 2.

The invention briefly described consists of a container comprising a rack for receiving cigars and including a plurality of compartments. Each compartment comprises a pair of telescoping tubular members adapted to be moved into extended position as shown in Fig. 2 for storing cigars and adapted to be moved into retracted position as shown in Fig. 3 for rendering the cigars accessible. Means is also provided for supporting cigarettes in the container. A cover is provided for enclosing the cigars and cigarettes

and the cover is adapted to be moved into elevated position as shown in Fig. 3 when access to the cigars and cigarettes is desired. Further details of the invention will 60 appear from the following specification.

The container comprises a base 10 disposed in and preferably secured to a tray 11. The tray 11 may contain lighters 12 and cutters 12^a as shown in Fig. 1. 65

The base 10 has an annular support 13 at its upper end in which is secured an annular rack 14 having a plurality of tubular compartments 15 for receiving cigars.

A frame 16 is slidably mounted with 70 reference to the base and tubular members 15 and this frame carries a plurality of tubular members 17 adapted to slide on and telescope with respect to the tubular members 15. The frame 16 has a tray 18 and 75 is provided with a plurality of radially arranged cigarette holding racks 19 for supporting the cigarettes in upright position in the tray 18.

The frame 16 is provided with a central 80 bushing 20 which is slidably mounted in a vertical post 21 and the post 21 is in turn slidably mounted in a transverse supporting strip 22 carried by the base 10. The post 21 extends upwardly through an opening 85 23 in the rack 14 and through a tubular member 24. The member 24 is secured to the bushing 20 and has formed on its upper end a flange 25 through which the post 21 90 extends. A handle 26 is secured to the upper end of the post 21 and a cross bar 27 is secured to the lower end of the post 21.

Means is provided for normally retaining the frame 16 in elevated position as shown in Fig. 2 and this means consists of a spring 95 20 interposed between the strip 22 and the bushing 20. The upward movement of the frame and of the post 21 is limited by the cross bar 27 which in the position shown in Fig. 2 engages the under side of the strip 22. 100

In order to retract the frame 16 and render the cigars accessible the user will press downwardly on the handle 26 thereby forcing the tubular member 21 and frame 16 carried thereby to the position shown in Fig. 3 wherein it will be seen that the cigars extend above the compartments and may be readily withdrawn therefrom. When the handle 26 is in the position shown in Fig. 2 and is pressed downwardly the cross bar 110 27 will pass through a slot 31 formed in a cross member 32. If the user then desires

to retain the frame in retracted position as shown in Fig. 3 he will turn the handle 26 to the position shown in said figure in which position the cross bar 27 will extend across the slot and will engage the under surface of the member 22.

The container is adapted for storing cigars and cigarettes as well as for dispensing them and in order to keep them in condition when they are being stored a cover is provided for enclosing the compartments. The cover 33 is slidably mounted on the tubular member 23 and the upper end 34 of the cover has a circular opening 35 and diametrically opposed notches 36 extending laterally from the circular opening. The cover also has a cross strip 37 therein and this strip is engaged by lugs 38 formed on a sleeve 39 and extending outwardly through longitudinal slots 40 formed in the tubular member 24. The sleeve 39 is disposed within the member 24 and is slidably mounted on the rod 21. A spring 41 is interposed between the bushing 20 and the sleeve 39 and tends to force the cover 33 to its elevated position as shown in Fig. 3. The cover may however be pressed downwardly to the position shown in Fig. 2 and may be locked in this position in the following manner. The tubular member 24 has formed on its outer surface a pair of longitudinally extending ribs 42 terminating at their lower ends at 43. The notches 36 normally receive the ribs 42 and permit the cover to be moved longitudinally on the member 24. When the user, however, desires to lock the cover in its lower position shown in Figs. 1 and 2, the cover is rotated on the tubular member 24 to a position in which the notches 36 will not register with the ribs 42. Upward movement of the cover will thereupon be prevented by the engagement of the upper end 24 of the cover with the lower ends 43 of the ribs. The cover 33 is provided with a perforated screen 45 and if desired a sponge may be placed in the cover above the screen to keep the cigars and cigarettes from becoming too dry. In order to prevent the cover 33 from being lowered too far in case the frame 16 is retracted to the position shown in Fig. 3, stop members 46 are mounted on the rack 14 and extend upwardly as shown in Fig. 1 a sufficient distance to limit the downward movement of the cover 33 thereby preventing the cover from engaging the exposed upper ends of the cigars. The operation of the device will now be briefly described. The container as shown in Figs. 1 and 2 is entirely enclosed by the cover 33 which is locked in its lower position in the manner hereinbefore set forth. When the user desires to render the cigars and cigarettes accessible the cover 33 will

first be rotated to a position in which the notches 36 will register with the ribs 42 whereupon the spring 41 will force the cover upwardly to the position shown in Fig. 3. The user will then press downwardly on the handle 26 forcing the cross bar 27 through the slot 31 and if he desires to retain the frame 16 in retracted position the handle will be rotated to cause the cross bar to engage the lower surface of the member 32. Cigars and cigarettes may then be drawn from the container. To close the device the handle 26 is again rotated until the cross bar 27 registers with the slot 31 whereupon the spring 30 will force the frame 16 and tubular member 24 upwardly to the position shown in Figs. 1 and 2. The cover 33 may be then depressed and locked in position in the manner already set forth.

Although one specific embodiment of the invention has been particularly illustrated and described, it will be understood that the invention is capable of modification and that changes in the construction and in the arrangement of the various cooperating parts may be made without departing from the spirit or scope of the invention as expressed in the following claims.

What I claim is:

1. A container comprising a rack for receiving cigars having a pair of hollow telescoping members for receiving cigars and a cover for said rack.
2. A container comprising a rack having a plurality of tubular compartments for receiving cigars, each of said compartments comprising a pair of telescoping members and a cover for said rack.
3. A container comprising a cigar rack having a plurality of compartments for receiving cigars, said compartments comprising sets of telescoping tubular members and means for sliding one set of said members on another set of members in one direction.
4. A container comprising a cigar rack having a plurality of compartments for receiving cigars, said compartments comprising sets of telescoping tubular members and resilient means for sliding one set of said members on another set of members in one direction.
5. A container comprising a cigar rack having a plurality of compartments for receiving cigars, said compartments comprising sets of telescoping tubular members, resilient means for sliding one set of said members on another set of members in one direction, and means for moving said members in the opposite direction against the action of said resilient means.
6. A container comprising a cigar rack having a plurality of compartments for receiving cigars, said compartments comprising sets of telescoping tubular mem-

bers, resilient means for sliding one set of members outwardly on another set of members in one direction, and means for moving said members in the opposite direction against the action of said resilient means.

7. A container comprising a cigar rack having a plurality of compartments for receiving cigars, said compartments comprising sets of telescoping tubular members, resilient means for sliding one set of members outwardly on another set of members in one direction, means for moving said members in the opposite direction against the action of said resilient means, and means for retaining said members in retracted position against the action of said resilient means.

8. A container comprising a cigar rack having a plurality of compartments for receiving cigars, each compartment comprising a pair of telescoping tubular members, resilient means for moving one set of said tubular members outwardly on the other set of members to form elongated compartments, and means for retracting the movable set of members on the other to render the cigars accessible.

9. A container comprising a cigar rack having a plurality of compartments for receiving cigars, each compartment comprising a pair of telescoping tubular members, resilient means for moving one set of said tubular members outwardly on the other set of members to form elongated compartments, means for retracting the movable set of members on the other to render the cigars accessible, and means for holding said movable set of members in retracted position.

10. A container comprising a cigar rack having a plurality of compartments for receiving cigars, each compartment comprising

ing a pair of telescoping tubular members, resilient means for moving one set of said tubular members outwardly on the other set of members to form elongated compartments, means for retracting the movable set of members on the other to render the cigars accessible, and a cover for enclosing said compartments when said two sets of tubular members are in extended position.

11. A container comprising a rack, a frame adapted to telescope thereon, resilient means to move said frame outwardly on said rack and means for moving said frame to retracted position on said rack.

12. A container comprising a rack, a frame adapted to telescope thereon, resilient means to move said frame outwardly on said rack, means for moving said frame to retracted position on said rack, and means for holding the frame in retracted position.

13. A container comprising a rack for cigars, a vertically movable cover therefor, resilient means for moving the cover bodily away from the rack and means for locking the cover in closing position on said rack.

14. A container comprising a base, a cigar rack mounted thereon, a post carried by the base, a telescoping frame carried by the post and having portions forming extensions of said rack and a cigarette rack carried by said frame.

15. A container having a plurality of tubular compartments for cigars, means for supporting a plurality of cigarettes in upright position and means for enclosing said compartments and said cigarette holding means.

In witness whereof, I have hereunto set my hand this 26th day of January, 1923.

WULF SILVERMAN.
